HEATING APPARATUS

Bernard Goerg, Bronxville, N. Y., assignor to American Radiator & Standard Sanitary Corporation, New York, N. Y., a corporation of Delaware

Application April 21, 1942, Serial No. 439,817

3 Claims. (Cl. 110—178)

This invention relates to furnaces and the like and more particularly to furnaces which are provided with foot-operated mechanism for opening the furnace door, and my invention has for its broad object to provide apparatus of this type which is of improved construction and arrangement of parts.

A further object is to provide apparatus of the above type which is simple in construction, inexpensive, and highly effective and dependable in operation.

The invention consists in the novel construction and combination of parts, to be more fully described hereinafter, and the novelty of which will be particularly pointed out and distinctly claimed.

In the accompanying drawings, to be taken as a part of this specification, I have fully and clearly illustrated a preferred embodiment of my invention, in which drawings—

Fig. 1 is a front elevation of a furnace constructed in accordance with the present invention, certain of the parts being broken away to illustrate more clearly the construction and operation of the apparatus;

Fig. 2 is a fragmentary vertical section of the apparatus shown in Fig. 1 and is taken on the line 2—2 of Fig. 1, and showing the relative position of the parts when the furnace door is in closed position and the mechanism for opening the door in its normal or initial position;

Fig. 3 is a view like Fig. 2 and shows the relative position of the parts when the door-opening mechanism is in the position occupied when the door is being opened;

Fig. 4 is an enlarged fragmentary plan section taken on the line 4—4 of Fig. 1; and

Fig. 5 is a perspective view showing the foot-operated lever and the door-opening push rod apart from the other parts of the furnace and in the relative positions which they occupy when assembled in the furnace.

For the purposes of illustration only, I have shown my invention as embodied in a boiler furnace 10 of the well known vertical sectional type. It will be appreciated, as the description proceeds, that the present invention can equally as well be embodied in any other kind of furnace. The furnace 10 comprises an upwardly extending front wall 11, having an access opening 12 formed therein and through which the fuel such as coal or coke may be shovelled into the furnace. The firing opening 12 is adapted to be closed by a fire door 13 suitably hinged, as indicated at 14, along one of its upright sides to the

wall 11. The door is provided at its other upright side with the usual catch 15 which is adapted to engage over a hook member 16 projecting outward from the wall 11, and thereby providing a latch for holding the door closed. A knob or handle 17 attached to the door 13 serves as a means for opening and closing the door by hand. The drawings also show a lower ash pit door 18 and an upper clean-out door 19.

In accordance with the present invention, I have provided an improved form of mechanism, indicated in general by the reference character 20, for opening the firing door 13 by the simple act of pressing down on a treadle lever with the foot, and this leaves the hands free to handle the fuel shovel, as is desired when firing the furnace. The foot-operated mechanism 20 comprises, in general, a treadle lever 21 adapted to be operated by the foot, and a push rod 22 moved upward and lengthwise thereof by the lever 21, and the upper end of the rod is so constructed and positioned with respect to the door as to engage a part on the inner side of the door 13 and force the door open upon such upward lengthwise movement of the rod 22. The structure of the lever 21 and rod 22 can best be seen in Fig. 5 which shows these parts in detail perspective and in their assembled relation.

The treadle lever 21 is pivotally supported, i. e., fulcrumed, between its ends, and thus comprises a first lever arm 23 at one side of the pivot positioned so that it can be pushed downward by the operator's foot, and comprises a second lever arm 24 at the other side of the pivot which is formed at its outer end with an upwardly opening socket 25. The fulcrum or pivotal support for the treadle lever 21 is provided by a suitable pivot pin 26 here shown to be in the form of a shoulder screw carried by the front wall 11 and extending outward from the wall and in a direction approximately normal to the plane of such wall.

The lower end of the rod 22 rests within the socket 25 and on an upwardly facing surface thereof. The rod 22 extends upward along the wall 11 and the upper end of the rod is formed with an integral outwardly projecting wedge-shaped member 27 which is located so that it will be behind the door 13 when the latter is closed, i. e., between the inner side of the door 13 and a part of the wall 11. The member 27 comprises an inclined or beveled upper surface 28 extending outward and downward from the wall 11.

When the door 13 is closed, the rod 22 is

in its normal or initial low position, the position shown in Figs. 1 and 2. In this position the inclined upper surface 28 is just below the lower outer edge or face 29 of a flange 30 which is formed on the inner side of said door and at a point spaced horizontally across the door from the hinged side thereof. When the rod 22 is in initial position the treadle lever 21 is substantially horizontal (see also Figs. 4 and 5). Thus, when the lever arm 23 is pushed downward by the foot, the rod 22 is given an upward lengthwise movement which results in the upper inclined surface 28 engaging the edge 29 and in the door being first lifted so that the catch 15 clears the hook 16 and then being forced outward toward open position. Fig. 3 of the drawings shows the lever arm 24 and the rod 22 as having been moved to their uppermost position and shows the door 13 as unlatched and moving outward about its hinge and in the direction of the arrow toward open position.

The push rod 22 is guided during such upward lengthwise movement by a suitable pin 34 here shown as a shoulder screw fixed at one of its ends to the wall 11 and projecting outwardly therefrom and fitting within a slot 35 formed in the rod and extending lengthwise of the latter. The pin 34 and slot 35 permit the rod 22 to slide freely in a lengthwise direction and they thus provide for the return of the rod to its initial low position by its own weight as soon as the operator removes his foot from the lever arm. Downward movement of the rod 22 is limited due to the under side of the outer end of lever arm 24 striking the upper surface of an inwardly extending ledge 37 forming a part of the base extension of the wall 11. For this purpose, the pivot pin 26 which forms the fulcrum support for the lever 21, is secured to a base part 38 of the wall 11 adjacent the ledge 37 and the outer part of the lever arm 24 which carries the socket 25 is set inwardly so that it will overlie and engage the ledge 37 and thereby limit downward movement of the rod, as just explained.

In the cast-iron boiler furnace shown, the wall 11 comprises the front of front boiler casting 40 and the front of a cast-iron base section 41, on which the boiler sections rest and are supported. The front of the cast-iron base section comprises the base 38 and the ledge 37, previously described, and also comprises an upwardly extending main wall part or section 42. It is noted that the front face of boiler section 40 is an upward extension of the main wall section 42, and therefore may be considered as an upper part of said section 42. The drawings show the wall section 42 as being spaced inwardly from the front face of the base part 39 and the rod 22 as lying closely alongside said section 42 and overlying the ledge 37. The door opening 12 forms the outer end of a horizontal passage 44 extending through the front section 40. The outer or forward part of the passage 44, including the opening 12, is defined by a flange 45 shaped substantially as a rectangle and extending forward from the front boiler section 40 and terminating outwardly in a ground vertical face 46 against which the door 13 engages when closed. Because of the fact that the face 46 is spaced forwardly of the upwardly extending main wall section 42, it is possible to locate the push rod 22 alongside the wall section and to locate the upper wedge-shaped end 27 thereof between the closed door 13 and the wall section

42. The inwardly set socket portion 25 on the end of the lever arm 24 also contributes to the above-described desired location of the rod 22 and to the ease, simplicity, and efficiency with which the force created by the foot of the operator is applied through the rod 22 to the edge or face 29 of flange 30 for opening the door.

In addition to the main wall section 42 which constitutes an inner wall part, the front wall 11 also comprises an outer wall part provided by a sheet metal jacket 48 spaced outward from the inner wall part to provide a passage 49 therebetween, which extends upward from the ledge 37 and to at least the flange 45. The outer jacket wall 48 is cut away at its bottom to form an opening 50 through which the inwardly set outer end of the lever arm 24 extends, and the wall 48 is also provided at the upper end of passage 49 with an upper opening 51 through which the wedge-shaped upper end 27 of the rod 22 extends. By reason of this wall construction, only the treadle lever 21 and the extreme bottom end of the rod 22 are exposed to view when the door 13 is closed. It is noted that the socket member 25 is open at its rear or inner side, as indicated at 52. This provides a simple and effective way for operatively connecting the rod 22 and lever 21 after the rod is mounted within the wall and with the jacket 48 in place.

From the above, it will be apparent that I have provided a simple and improved form of foot-operated mechanism for opening a furnace door. With the exception of the two shoulder screws 26 and 34, there are only three parts to the mechanism. One of these parts, the flange 30, is cast integral on the furnace door at little, if any, increased cost, and the other two parts, the rod 22 and lever 21, are simple castings which can be produced at a very low cost. The two shoulder screws 26 and 34 can be of standard size and hence will also cost very little. It will be noted from an examination of Fig. 1 that the push rod is slightly inclined from the vertical. This arrangement permits the location of the treadle lever 21 at the side of the ash pit door 18 where it is easily accessible to the foot of the operator. As the rod 22 is located alongside the main wall section and within the passage 49, the rod lies and moves in a plane which is also behind the ash pit door and hence does not interfere with the opening and closing of the latter. Consequently, the rod 22 can be made straight which is the most efficient form for the purpose of transmitting the force for opening the door.

What I claim and desire to secure by Letters Patent of the United States is:

1. In furnace apparatus, a wall including an upwardly extending base, a ledge extending inwardly from the top of said base, and a main wall section extending upwardly from the inner edge of the ledge and having an opening therethrough; a door closing said opening; a lever pivotally supported on said wall adjacent said ledge with the pivotal axis arranged substantially horizontal and between the ends of said lever to provide a first lever arm adapted to be engaged and pressed down by the foot of the operator from a normal or initial position, and a second lever arm including a portion at the outer end thereof overlying and engaging the top of said ledge when in said initial position; and a push rod operatively engaging at its lower end an upwardly facing surface on the outer end of said second lever arm and said rod extending upward therefrom to said door and in-

cluding an upper portion so formed as to engage a portion of said door and force the latter open upon an upward lengthwise movement of said rod from said initial position; and means for guiding said rod during its upward lengthwise movement and providing for the return of said rod and said lever to initial position due to the weight of said rod when said first arm is released by the operator.

2. In a furnace, an upwardly extending wall having an access opening therethrough; a door closing said opening and being hinged along an upright side thereof to swing outwardly to open position; said wall including inner and outer wall parts defining a passage extending upward from a lower part of said wall to a point located behind said door when the latter is closed, said outer wall part having upper and lower openings adjacent the upper and lower parts of said passage, respectively; an upwardly extending push rod arranged lengthwise in said passage and including a portion at its upper end extending outward through said upper opening and having an inclined upper surface extending outward and downward and beneath a surface formed on said door so that when said push rod is moved upward said inclined upper surface on said push rod engages said surface formed on said door to force said door open; a treadle lever located adjacent said lower opening and pivotally supported between its ends to provide a first lever arm positioned to be engaged and pushed downward by the foot of the operator, and a second lever arm extending through said lower opening and engaging the lower end of said push rod so

as to move the latter upward to open the door when said first arm is pushed downward.

3. In a furnace, an upwardly extending wall having an access opening therethrough; a door closing said opening and being hinged along an upright side thereof to swing outward to open position; said wall including inner and outer wall parts defining a passage extending upward from a lower part of said wall to a point located behind said door when the latter is closed, said outer wall part having upper and lower openings adjacent the upper and lower parts of said passage, respectively; a push rod arranged lengthwise in said passage and including an upper part extending outward through said upper opening and toward said door, and said upper rod part being so constructed and positioned with respect to said door as to engage the latter and force the door open upon an upward lengthwise movement of said rod; and a treadle lever at the exterior of said wall adjacent said lower opening and pivotally supported intermediate its ends on said wall to move about an axis projecting outwardly from said wall and providing a first lever arm positioned to be pushed downward by the foot of the operator, and a second lever arm having a portion at its end extending laterally through said lower opening and engaging the lower end of said push rod so as to move the latter upward to open said door when said first arm is pushed downward; the outer end of said second lever arm being formed as an upwardly opening socket receiving said push rod and being also open at the side adjacent said wall to facilitate assembly and removal of the parts.

BERNARD GOERG.
